UNITED STATES PATENT OFFICE

LINDSLEY SCHEPMOES, OF NEW HAVEN, CONNECTICUT, ASSIGNOR TO THE SAFETY CAR HEATING & LIGHTING COMPANY, A CORPORATION OF NEW JERSEY

LIGHTING FIXTURE

Application filed February 15, 1929. Serial No. 340,133.

This invention relates to lighting fixtures and more particularly to fixtures for lighting railway vehicles and the like.

An object thereof is to provide a novel and highly desirable form of light distributor for such fixtures. Another object is to provide a simple and practical fixture in the use of which direct and indirect lighting effects may be attained in a desirable and efficient manner. Other objects will be in part obvious and in part pointed out hereinafter.

The invention accordingly consists in the features of construction, combination of elements and arrangements of parts which will be exemplified in the structure to be hereinafter described and the scope of the application of which will be indicated in the following claims.

The accompanying drawings show one or more illustrative embodiments of my invention, wherein

Figure 1 is a diagrammatic plan view of a section of a car or other vehicle, disclosing one embodiment of my invention;

Fig. 2 is an illustrative transverse elevation of one of the fixtures shown in Fig. 1;

Fig. 3 is a longitudinal section thereof taken on the line 3—3 of Fig. 2;

Fig. 4 is a horizontal section thereof taken on the line 4—4 of Fig. 2; and

Fig. 5 is a similar horizontal section showing a modified form of distributor.

Similar reference characters refer to similar parts throughout the several views of the drawings.

Referring to Fig. 1 of the drawings, there is shown in diagrammatic form the usual arrangement of seats placed along the sides of a car with an aisle running the length of the car therebetween. The seats are indicated by the numeral 1, and the aisle by the numeral 2. At 3 are shown diagrammatically the disposition of a pair of fixtures, shown more in detail in Figs. 2, 3 and 4, mounted or suspended over the aisle within the car in a manner commonly employed in car lighting, that is, with a fixture arranged above and between a pair of seats, and another fixture arranged above and between a second pair of seats, with a third pair of seats arranged so as to re-

ceive lighting effects from said two fixtures. With such an arrangement, it is desirable that the alternate seats, which are not provided with fixtures, should receive substantially equal illumination with those more advantageously placed. This end, the form of fixture embodied in this invention and shown in Fig. 1 is well adapted to attain, for by the combination of light reflection and light diffusion resulting from the use of the present form of fixture, the plane of illumination upon each side of the aisle may be made to receive practically uniform illumination at each seat, and this without objectionable glare. It will be readily understood that the occupants of seats located laterally of any particular fixture will not be affected by glare from said fixture, unless they look up directly at the fixture. On the other hand, a fixture having the source of light unshielded and located some distance ahead of a seat occupant, coming within the direct range of vision, is liable to produce an unpleasant glare. Then, too, passengers passing along an aisle when directly facing a series of such fixtures may well be disturbed by the glare from some of them.

With the present form of fixture disposed as illustrated, this trouble is obviated, for direct lighting effects are only had throughout a limited zone directly beneath and laterally of each fixture. From all other points the source of light in the fixture is concealed, while uniform illumination is attained by reason of the efficient and pleasing combination of reflecting and diffusing surfaces interposed between the source of light and the observer.

Now referring to Figs. 2, 3 and 4 for a more detailed description of the fixture disclosed therein, a source of light is shown comprising a pair of spaced incandescent lamps 4, mounted in any desired manner so as to depend from the ceiling 5 of the vehicle. A base for the fixture is shown, which may be of any conventional form but which in the present instance is shown to comprise a member 6 provided with flanges 7, by means of which it may be secured to the edges of an opening 8 in said ceiling. The light-distributing

means employed comprises a plurality of substantially vertically disposed plates, indicated generally by the numeral 9, arranged advantageously to produce the light effects hereinbefore mentioned. These plates may be made of translucent material, such as opal or frosted glass, but preferably a moulded non-frangible material, as, for example, the casein product galalith and bakelite; or some of them may be translucent and others opaque. In the specific structure shown, the lamps 4 are arranged side by side longitudinally of the car. Between them is disposed a plate member 10, and partially surrounding the sides opposite the plate 10 are plates 11 and 12, which may be made in the form shown in Fig. 4 or in the modified form shown in Fig. 5, or be made in various other forms suitable for the purpose for which they are employed. Other plates 13, 14 and 15 are arranged in spaced parallel relation to each other and to the plate 10, with their inner edges overlapping the outer edges of the plates 10, 11 and 12, said edges being directed substantially toward the lamps, as is clearly illustrated in Fig. 4.

It will be seen by reference to Fig. 4, that light rays from each of the lamps will pass directly through its respective member 11 or 12 and be diffused thereby to spread the light evenly on the ceiling and in the aisle of the car and downwardly toward the seats. The plate 10, whether made opaque or translucent, serves mainly as a reflecting member, taking the rays of light from both lamps and bending them back against the adjacent surfaces of the plates 13, 14 and 15, where they may again be inwardly reflected, or, in case the said last plates are made of translucent material, be diffused outwardly. But these plates 13, 14 and 15 also receive light directly from the lamp units, and probably by indirect reflection from the plate members 11 and 12, so that the said plates serve as reflectors from both surfaces, and also their two surfaces distribute light by diffusion.

In the modification shown in Fig. 5, the plates 13, 14 and 15 are brought together at their outer edges. In this case, the plates would transmit light by reflection and diffusion of light rays received directly from the lamp units upon their outer surfaces. They would also diffuse light received upon their inner surfaces by reflection from the plate 10.

It will be clear, then, that with either form of fixture, direct lighting would be obtained only throughout limited zones laterally disposed with respect to each fixture, where, as stated above, a certain amount of glare may not be objectionable, and where more intense lighting effects may be of advantage; whereas, the area outside of said zones will receive only indirect or semi-direct illumination, and from all points outside of said zones the lamp elements themselves will be invisible,

so that under normal conditions no glare can reach the eyes of passengers.

As many possible embodiment may be made of the above invention and as many changes might be made in the embodiments above set forth, it is to be understood that all matter hereinbefore set forth or shown in the accompanying drawings is to be interpreted as illustrative and not in a limiting sense.

I claim:

1. In lighting fixtures, in combination, a source of light, and light-distributing means associated therewith, said means comprising a plurality of spaced plate-like members arranged about said source in a plurality of relatively staggered overlapping groups.

2. In lighting fixtures, in combination, a source of light, and light-distributing means associated therewith, said means comprising a plurality of spaced plate-like members arranged about said source in a plurality of relatively staggered overlapping groups, certain of said members being disposed and adapted to function principally by reflection and others being disposed and adapted to function principally by diffusion.

3. In lighting fixtures, in combination, a pair of lamp units, and light-distributing means associated therewith, said means comprising a plurality of spaced plate-like members arranged about said lamp units in a plurality of relatively staggered overlapping rows.

4. In lighting fixtures, in combination, a pair of lamp units, and light-distributing means associated therewith, said means comprising a plurality of spaced plate-like members arranged about said lamp units in a plurality of relatively staggered overlapping rows, the members of one of said rows being intersected by a plane passing through the axes of said lamps and the members of others of said rows being disposed laterally of said plane, whereby certain of said members function principally by reflection and others function principally by diffusion.

5. In lighting fixtures, in combination, a pair of plate-like members, a source of light disposed between said plate-like members, and other plate-like members disposed in staggered relation between and overlapping the outside edges of said pair of plate-like members.

6. In lighting fixtures, in combination, a pair of plate-like members, a source of light disposed between said plate-like members, and other plate-like members disposed in staggered relation to and overlapping the outside edges of said pair of plate-like members.

7. In lighting fixtures, in combination, a pair of spaced lamp units, a plate-like member disposed adjacent the relatively inner sides of said units, a pair of plate-like mem-

bers disposed respectively adjacent the relatively far sides of said units, and other plate-like members disposed in staggered relation between and overlapping the outside edges of said first and said second plate-like members.

8. In lighting fixtures, in combination, a lamp unit, and a plurality of independent non-contiguous plate-like members disposed about the sides of said unit to give direct illumination throughout a limited zone, substantially parallel with a plane passing through an axis of said unit and to prevent direct illumination at all points outside of said zone.

9. In lighting fixtures, in combination, a lamp unit, and a plurality of independent non-contiguous plate-like members disposed about the sides of said unit to give direct illumination throughout a limited zone, substantially parallel with a plane passing through an axis of said unit and to give semi-direct illumination at all points outside of said zone.

10. In lighting fixtures, in combination, a pair of spaced lamp units, and light-distributing means associated therewith, said means comprising a plurality of spaced overlapping translucent plates arranged about and between said units in a manner to give direct illumination at points within limited zones upon either side of a plane passing through the axes of said units and to prevent direct illumination at all points outside of said zones.

11. The combination with a vehicle having a center aisle and a ceiling, of a pair of spaced lighting units depending from said ceiling, and light-distributing means associated with said units, said means comprising a plurality of substantially vertical non-transparent plates arranged about said units so as to confine direct illumination from said units to the space immediately therebeneath and to the spaces disposed laterally thereof upon opposite sides of the aisle.

12. The combination with a ceiling of a vehicle having seats arranged upon either side of a center aisle, of a plurality of lighting fixtures suspended from the ceiling at spaced points above said aisle, each of said fixtures comprising a source of light, and light-distributing means, said means including a plurality of overlapping plate-like members arranged about said source to give direct illumination to the aisle directly therebeneath and to the seats disposed laterally thereof, and substantially uniform semi-direct illumination at all other points.

13. In lighting fixtures, in combination, a source of light comprising a pair of light units, and light-distributing means comprising plate-like members disposed laterally and exteriorly of said source on two sides thereof, and other plate-like members disposed re-

spectively between the units of said source and laterally of said source on two other sides thereof, said first members being disposed and adapted to conceal said source and to distribute light mainly by direct diffusion, said second members being disposed and adapted partially to reveal said source and to distribute light by direct and indirect reflection and by diffusion.

In testimony whereof, I have signed my name to this specification this 2d day of February, 1929.

LINDSLEY SCHEPMOES.
